(57) **CLAIM**

The ornamental design for a short-pipe p-trap, as shown and described.

DESCRIPTION

FIG. 1 is a three dimensional view of the short-pipe p-trap. The section cut line for FIG. 9 is also shown.

FIG. 2 is a front view of the short-pipe p-trap.

FIG. 3 is a rear view of the short-pipe p-trap.

FIG. 4 is a left side view of the short-pipe p-trap.

FIG. 5 is a right side view of the short-pipe p-trap.

FIG. 6 is a top view of the short-pipe p-trap.

FIG. 7 is a bottom view of the short-pipe p-trap.

FIG. 8 is an exploded view of the elements of the short-pipe p-trap; and,

FIG. 9 is a cross-section view of the short-pipe p-trap cut at the line shown in FIG. 1.

The short-pipe p-trap is a distinctive plumbing piping insertable device used for creating or replacing a p-trap function in a drain pipe.
